CLAIM

The ornamental design for a tool holder as shown and described.

DESCRIPTION

FIG. 1 is a top-front perspective view of the tool holder, showing our new design having a front half connected to a rear half.

FIG. 2 is a bottom-rear perspective view of the tool holder of FIG. 1.

FIG. 3 is a front view of the tool holder of FIG. 1, wherein the right side and the left side of the tool holder, having right and left wings, are at the right and left of the sheet, respectively.

FIG. 4 is a right side view of the tool holder of FIG. 1.

FIG. 5 is a left side view of the tool holder of FIG. 1.

FIG. 6 is a rear view of the tool holder of FIG. 1.

FIG. 7 is a top view of the tool holder of FIG. 1.

FIG. 8 is a bottom view of the tool holder of FIG. 1.

FIG. 9 is a top-front perspective view of the tool holder of FIG. 1, holding two exemplary hex wrenches shown in broken lines.

FIG. 10 is a bottom-rear view of the tool holder of FIG. 1, holding two exemplary hex wrenches shown in broken lines.

FIG. 11 is a front view of the tool holder of FIG. 1, holding two exemplary hex wrenches shown in broken lines.

FIG. 12 is a right view of the tool holder of FIG. 1, holding two exemplary hex wrenches shown in broken lines.

FIG. 13 is a left view of the tool holder of FIG. 1, holding two exemplary hex wrenches shown in broken lines.

FIG. 14 is a rear view of the tool holder of FIG. 1, holding two exemplary hex wrenches shown in broken lines.

FIG. 15 is a top view of the tool holder of FIG. 1, holding two exemplary hex wrenches shown in broken lines.

FIG. 16 is a bottom view of the tool holder of FIG. 1, holding two exemplary hex wrenches shown in broken lines.

FIG. 17 is a front perspective view of the rear half of the tool holder of FIG. 1 that has been disconnected from the front half of the tool holder of FIG. 1, the rear side of the front half being circular and planar.

FIG. 18 is a front view of the rear half of FIG. 17.

FIG. 19 is a right view of the rear half of FIG. 17.

FIG. 20 is a left view of the rear half of FIG. 17.

FIG. 21 is a back view of the rear half of FIG. 17, which is the same as the rear view of FIG. 6 of the tool holder.

FIG. 22 is a top view of the rear half of FIG. 17.

FIG. 23 is a top view of the rear half of FIG. 17; and,

FIG. 24 is a front view of the tool holder of FIG. 1, connected to an exemplary prosthetic leg shown in broken lines by an elastic band passing around a post of the prosthetic leg and the right and left wings of the tool holder.
